SHOE CONSTRUCTION

John E. Langley, Brooklyn, N. Y.

Application November 5, 1934, Serial No. 751,647

1 Claim. (Cl. 36—71)

The invention relates to a shoe construction and more especially to a combined heel cushion and arch support.

The primary object of the invention is the provision of an insert for a shoe, wherein the same functions as a heel cushion and arch support, as well as a flexible, semi-flexible or rigid insole and is permanently built into the shoe, so that when the latter is worn and the wearer places his heel or foot to the ground there is a general give at the heel which allows the weight of the body to settle in the shoe without a jar and as the weight presses down on the heel the yielding of the same will cause the said heel portion to be arranged below the plane of the arch portion of said insert and slightly bulge or arch the same so that in a further walking movement of the wearer the inner longitudinal arch of his foot will be brought against and rest in a natural way upon the said arched portion of the insert, and incident to its elasticity, the heel portion of the insert will be returned to its initial position, as the weight of the heel of the foot is relieved therefrom.

Another object of the invention is the provision of an insert of this character, wherein the same when in use prevents falling arches, as well as relieving weak arches.

A further object of the invention is the provision of an insert of this character, wherein there will be absorbed all shocks ordinarily transmitted to the human heel and arch in the act of walking, thus rendering walking easier and more pleasant.

A still further object of the invention is the provision of an insert of this character which is comparatively simple in construction, thoroughly reliable and efficient in its purposes, readily and easily built into a shoe, strong, durable, and inexpensive to manufacture and install.

With these and other objects in view, the invention consists in the features of construction, combination and arrangement of parts as will be hereinafter more fully described in detail, illustrated in the accompanying drawing, which discloses the preferred embodiment of the invention, and pointed out in the claim hereunto appended.

In the accompanying drawing:

Figure 1 is a vertical longitudinal sectional view through a shoe showing the insert constructed in accordance with the invention built therein.

Figure 2 is a plan view of the insole illustrating the insert associated therewith.

Figure 3 is a longitudinal edge elevation.

Figure 4 is a detail plan view of the insert removed from the insole.

Figure 5 is a front elevation of the same.

Similar reference characters indicate corresponding parts throughout the several views in the drawing.

Referring to the drawing in detail, particularly Figures 1 to 5 inclusive, there is illustrated a low shoe, a portion thereof being designated generally at A having, as usual, a whole outer sole 10 and a heel 11, these being covered by a whole insole 12, preferably formed from leather. This insole 12 is split from the heel end to the arch area 13 to provide a space or pocket 14 confronted by an upper lift 15 and a lower lift 16, respectively, the forward end of the space or pocket 14 being angularly edged, as at 17. The insole 12 is also split from the toe end to the arch area 13, as at 18, to render the front portion or the sole part of said insole flexible. The lower lift 16 of the insole 12 may have attachment with the outer sole 10 and the heel 11 by fasteners, such as nails 19.

Received in the pocket 14 is the combined heel cushion and arch support comprising a body 20, preferably made from rubber, although it may be made from any flexible material or metal, and conforming to the contour of the heel end of the shoe, while at the forward end of this body 20 is the curvilinear-shaped horn 21 functioning as an arch support, the body 20 being confined in the pocket 14 between the upper and lower lifts 15 and 16 of the insole 12 and in the use thereof the

said insert will function to absorb shocks ordinarily transmitted to the human heel and arch in the act of walking when the shoe is worn, as well as preventing the delicate bone of the heel of the foot from coming in contact with the fasteners 19 securing the sole 10 and the heel 11 to the upper of the shoe A. My insert is designed to impart to the foot the same soft effect as were a person, employing the same, walking barefooted over a sandy or like yieldable surface.

When standing the main weight of a body is directed onto the heel of the foot and with my insert the heel portion of the insert will be compressed in a gentle manner so that the same will be arranged below the arch portion of said insert and therefore such arched portion will be arranged to properly contact with the arch of the foot and the horn will be arranged against the side of the foot. This, of course, is true with respect to the rocking of the foot in walking.

In the working of the insert the compression of the heel portion of the said insert creates a slight bulge at the arch thereof which causes the horn to be brought into snug contact with one side of the foot.

What is claimed is:

A shoe having an inner sole of readily flexible material which is centrally slit transversely from its toe and heel portions to present upper and lower lifts, the slit from the toe end of the inner sole terminating in a straight transverse wall which is arranged forwardly of the shank of the shoe and the slit at the heel portion of the inner sole terminating in an angle wall which is di-

rected from the forward end of the shank at one side of the shoe to the forward end of the heel at the second side of the shoe, and an insert received between the lifts at the heel portion of the shoe having a tapered end which contacts with the angle wall between said lifts, and having a horn on one of its edges to rest against the shoe at the waist thereof. 5

JOHN E. LANGLEY.
